UNITED STATES PATENT OFFICE.

DONALD J. MURRAY, OF WAUSAU, WISCONSIN.

GANG SAWING MACHINE.

SPECIFICATION forming part of Letters Patent No. 288,723, dated November 20, 1883.

Application filed July 16, 1883. (No model.)

To all whom it may concern:

Be it known that I, DONALD J. MURRAY, a citizen of the United States, residing at Wausau, in the county of Marathon and State of Wisconsin, have invented certain new and useful Improvements in Gang Cut-Off Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention is a gang cut-off machine for preparing slabs or bolts for sawing into laths, palings, and other similar articles, and embraces the following peculiar features: a saw-frame table having the arbor-rails upon which 20 the saws are each independently mounted upwardly inclined from front to rear; also, the said saws, being of any required uneven number, are mounted in successive line and approaching pairs, commencing with the front 25 and outside pair until the single saw is reached, which is placed in the exact middle and extreme rear of the table-frame; and, also, the single-bar links of the transfer-chains are each furnished with a flat-faced, rear-pointing, and 30 chisel-edged hook, all of which and their purposes are hereinafter more fully described, and illustrated by the accompanying drawings, in which the same letters designate identical parts of my invention in the different figures, 35 respectively.

Figure 1 illustrates an end view of my saw-frame, showing the inclined arbor-rails, the one each of two pairs of independently-mounted saws, and the single saw at the middle rear, 40 together with the hook - provided transfer-chain. Fig. 2 illustrates a plan view of the same, showing the relative positions of the line-pairs of saws and the timber-feeding transfer-chains. Fig. 3 illustrates both a side and top 45 view of a section of transfer-chain.

The letter A represents my gang-saw frame, which is constructed of suitable length to mount at least three saws, although they may amount to any desired uneven number, and

with saw-arbor rails *d*, upwardly inclined from 50 the front to the rear sides.

The letters *a a*, *b b*, and *c* represent the gang-saws, numbering five, as herein shown. These saws are each mounted on an independent arbor and placed as follows: The saws *a a*, forming the first of said line-pairs, are mounted one on the outer side of each end arbor-rail, and set in line sufficiently back from the front edge of the table to allow a length of slab-board or other piece of bolt-timber to be placed 55 on the chains in front of said saws. The next pair of saws, *b b*, are set in line about eighteen inches back of the line of the pair *a a*, and also at sufficient distance within the said first pair to cut off equal and proper lengths of lath or 60 paling bolts; and the last or fifth saw is set exactly in the middle between and also about eighteen inches back of the line of the last pair of saws, *b b*, to cut into two equal parts or lengths 65 the slab which has just passed said saw. 70

The letters C and D represent, respectively, the double and single bar links of one of the transfer-chains, which travel, over suitable rollers, up the inclined saw-table to feed the timber to the saws.

The letter *h* represents the chisel-edged hook, which is fastened into the top of each single-bar link of the transfer-chains, to catch the timber and carry it to be cut, past the saws when cut, and over the upper side of the table. 80 The inclination of the table also serves to hold the timber firmly against the hooks, and their chisel-edges and flatsides do not mar the surface of the timber like pointed ones are liable to do. 75

The operation of my machine is as follows: 85 A chosen slab or board is thrown upon the table A, and, being caught by the hooks *h* on the transfer-chains, is carried by these up the inclined table against the first line and outer pair of saws, *a a*, which trim off the ends of 90 the slab. Then, being passed to the saws *b b*, two equal lengths are cut from the outer ends of the timber, which, being passed on to the last or single saw, is cut by it into other equal lengths, which completes the operation. As 95 only two saws engage and cut the timber at one time, the strain is much less than when all the saws are engaged at once, and, besides, the

timber is never pushed off the hooks. Therefore,

Having fully described my invention, what I claim as new, and desire to secure by Letters 5 Patent, is—

1. In a frame-table, A, the arrangement of its saws, of any uneven number and independently mounted upon the saw-arbor rails d, in successively and equally approaching and lateral line-pairs, commencing with the front and outside line-pair, a a, then the next line-pair, b b, and so on until the rearmost, middle, and single saw, c, is reached, substantially as and for the purposes herein specified.

2. The combination of the chisel-edged, flat-faced, and rear-pointing hooks h of the transfer-chain C D with the lateral line-pair saws a a and b b, and the rearmost, middle, and single saw, c, independently mounted in the saw-frame table A of a gang cut-off machine, as hereinbefore described, substantially as and for the purposes herein specified.

In testimony whereof I affix my signature in presence of two witnesses.

DONALD J. MURRAY.
